UNITED STATES PATENT OFFICE.

JOSEPH F. PETERMAN, OF SUPERIOR, WISCONSIN, ASSIGNOR OF ONE-THIRD TO JAMES PETERMAN, OF CHICAGO, ILLINOIS.

TRACK-BRACE.

1,361,901.

Specification of Letters Patent. Patented Dec. 14, 1920.

Application filed July 9, 1920. Serial No. 394,965.

To all whom it may concern:

Be it known that I, JOSEPH F. PETERMAN, a citizen of the United States, residing at Superior, in the county of Douglas and 5 State of Wisconsin, have invented certain new and useful Improvements in Track-Braces, of which the following is a specification.

This invention relates to a track brace for 10 laterally bracing the rails of a section of railroad track.

An important object of the invention is 15 the provision of a track brace which is primarily adapted to be used as a brace for rails upon curves, where powerful lateral stresses are imposed upon the rails by heavy and fast moving rolling stock.

A further object of the invention is the 20 provision of a track brace which will serve as a positive means for maintaining the proper gage of rails.

A further object of the invention is the 25 provision of a track brace of the above described character which is to be used in conjunction with a standard track construction, including lateral rail bracing angles or fish plates, for bracing the rails and preventing lateral vibration, or spreading of rail joints.

Other objects and advantages of the 30 invention will be apparent during the course of the following detailed description.

In the accompanying drawings forming 35 a part of this specification and in which like reference characters designate like parts throughout the same:

Figure 1 is a vertical cross section of a section of railroad track.

Fig. 2 is a plan view of a section of track.

Fig. 3 is a cross sectional view of a rail 40 taken on the line 3—3 of Fig. 2.

Fig. 4 is a cross section of a rail taken on the line 4—4 of Fig. 2.

Fig. 5 is a side elevation of a section of track.

Fig. 6 is a fragmentary cross sectional 45 view taken on the line 6—6 of Fig. 2.

Fig. 7 is a cross sectional view of a rail showing a modified arrangement of the track brace.

50 In the drawings, wherein for the purpose of illustration is shown a preferred embodiment of my invention, the letter A designates a rail supported upon a bed plate B and mounted upon ties C. Angle plates D 55 are provided of standard construction for

laterally bracing the web of rail A, while a bridle E, and clamping members F, are provided for use in conjunction with the standard track construction, for the rails thereof.

The rail A is preferably of the T type 60 comprising the head 10, web 11 and base 12. The web 11 of the rail A is ordinarily braced upon each side by angle plates 13 and where the rail is thought to be weak and where powerful lateral stresses are 65 sometimes encountered, the bolt 14 being provided to securely bolt the legs of the angle plates to the web 11 as is the standard construction.

The bed plate B is provided upon one longitudinal edge with an enlargement, or shoulder 15 which is adapted to abut against an outside edge 16 of the rail base, in such manner that when the spikes G are driven into the ties C through the apertures in the bed plates B as in standard construction, the shoulder 15 will resist any tendency of the rails to spread. It is to be noted that the shoulder 15 is only of such height that the upper surface of the shoulder will be flush 75 with the upper surface of the flange 16 forming the base of the T rail, when the bed plate is in position to support the rail.

The bridle member E is of sufficient length to span the trackway from rail to rail and is 80 adapted to be positioned beneath the bed plate B of the rail A and preferably intermediate the ties as is clearly shown in Fig. 2 of the drawings. The ends of the bridle member E are preferably provided with 85 hooked portions 20 integral therewith which are adapted for the purpose of receiving the enlarged portion or shoulder 15 of the bed plate B. Suitable apertures 21 and 22 are provided in the end of the bridle member E 90 and bed plate B respectively, which are adapted to receive a bolt 23 for rigidly securing the bed plate B within the hooked portion 20. From this construction it can readily be seen that the bridle E provides a 100 means whereby the rails A of the trackway are prevented absolutely from spreading.

The clamping members F are provided to be positioned between the rails of the trackway and are provided with apertures therein 105 for the reception of bolts 25 to be bolted directly to the bridle E. The clamping arm 26 of the clamp, which is provided to overlie the foot of the rail and the bed plate B, is provided with fillets 27 adapted to abut 110

against the edge of the base flange 16 and the edge of the bed plate B. From this construction it can now be seen that the rail is rigidly braced between the hooked portion 20 of the bridle member E and the clamp member F in such manner that the gage of the trackway can be accurately held.

Where the angle plates D are used as on a curve, it will be seen that an additional 10 bracing effect is produced since the leg 28 of the angle member D which lies upon the flange 16 of the base of the rail A abuts against the edge of the hooked portion 20 as is clearly shown in Fig. 4 of the drawings. 15 However, it will be necessary in this event to provide a special clamping member F since the clamping arm 26 has to overlie an additional thickness of metal, namely, the leg 28 on angle plate D. Where angle plates 20 D are used in which the flange 28, which overlies the flange 16 of the foot rail 16, is so short that it terminates short of the edge of the flange 16, as is shown in Fig. 7 of the drawings; it will be necessary, or rather desirable 25 to provide a bridle member E having a hooked member 20 which overlies the flange 16 and abuts against the edge of the flange 28.

From the foregoing it can be seen that a 30 comparatively simple, yet effective device is provided which is capable of meeting the various demands of standard railroad construction.

In operation it is merely necessary to remove 35 a few of the spikes G upon the rails, the bridle member E is then placed beneath the rail and the bed plates B slid in their positions beneath the rails and upon the ties C, and the bridle member securely bolted thereto by the bolts 23. Clamping members F are then placed upon the bridle members 40 between the rails and bolted thereto by bolts 25 or the like, in such manner that the clamping arm 26 overlies the foot of the rail and 45 the bed plate as hereinbefore described. Since the bridle member is now bolted to each rail it provides a means whereby the gage of the trackway can be accurately held.

It is to be understood that the form of my 50 invention herewith shown and described is to be taken as a preferred example of the same and that various changes in the shape, size and arrangement of parts may resort to without departing from the spirit of the 55 invention or the scope of the subjoined claims.

I claim:

1. In a rail brace, the combination with 55 ties, bed plates upon said ties and rails upon 60 said bed plates forming a section of track, of a bridle member beneath said plates having portions thereof engaging the outer side of the rail to prevent spreading of the rail, and detachable clamping members secured 65 to the bridle member on the inner sides of

the rails to hold the rails at a predetermined gage.

2. In a rail brace, the combination with the standard construction of a section of railroad track, including rails, rail bed 70 plates and ties, of a bridle member spanning said railroad from rail to rail, beneath the bed plates of the track way, said bridle member having hooked portions on the ends thereof engaging said bed plates upon the 75 outer sides of the rails of said trackway, and detachable clamping members upon the inner sides of said rails, mounted upon the bridle member for maintaining the track at a predetermined gage.

3. In a section of track comprising rails, bed plates, ties, and angle plates for bracing the webs of said rails, the combination of a bridle member transversely spanning said trackway from rail to rail, beneath the bed 85 plates thereof having hooked portions on the end thereof engaging said bed plates upon the outer sides of said rails of the trackway, and abutting against the angle plates upon the outer sides of said rails, and 90 clamping members mounted upon the inner sides of said rails, and bolted to the bridle member, overlying said bed plates and abutting against the angle plates upon the inside of said rails for maintaining the track at a 95 predetermined gage.

4. In a section of track comprising rails, ties and angle plates for bracing the webs of said rails, the combination of a bridle member transversely spanning said trackway from rail to rail beneath the rails thereof and having hooked portions on the ends thereof engaging said rails upon the outer sides of said rails of the trackway and abutting against the angle plates upon the outer 105 sides of said rails, and clamping members mounted upon the inner sides of said rails and bolted to the bridle member, overlying the base of said rails, abutting against the angle plates upon the inside of said rails for 110 maintaining the track at a predetermined gage.

5. In a track brace, the combination, with a section of railroad track comprising ties, and rails, of bed plates intermediate said 115 ties and rails having enlarged portions thereon projecting from the foot of the rail and upon the outer sides of the rails of the track section, a bridle member having hooked portions thereon adapted for engaging said enlarged portions of the bed plate for maintaining said enlarged portions in contact with the foot of the rail in such manner as to prevent spreading of the rails, and clamp members bolted upon the 120 bridle member upon the inner sides of said rails and engaging said rails whereby the 125 track is maintained at a predetermined gage.

6. In a track brace, the combination with
a section of track comprising ties, rails, an-
gle plates upon said rails for bracing the
webs thereof, of bed plates intermediate said
5 ties and rails having enlarged portions
thereon projecting from the foot of the rail
and upon the outer sides of the rails of the
track section, a bridle member having
hooked portions thereon adapted for engag-
ing said enlarged portions of the bed plates
0 for maintaining said portions in contact
with the foot of the rail to prevent spread-
ing of the rails, said hooked portions also
abutting against the angle plates upon the
outer sides of said rail, and clamping mem-
bers bolted upon said bridle member posi-
tioned between the rails and overlying the
foot of said rails and a portion of the an-
gle plates upon the inside of the rails for
maintaining the track section at a prede-
termined gage. 15 20

JOSEPH F. PETERMAN.
